UNITED STATES PATENT OFFICE

GEORGE F. BEACH, OF PHILADELPHIA, PENNSYLVANIA, ASSIGNOR, BY MESNE ASSIGNMENTS, TO RYAN, SCULLY & COMPANY, OF PHILADELPHIA, PENNSYLVANIA, A CORPORATION OF DELAWARE

FURNACE CONVEYER

Application filed April 8, 1926. Serial No. 100,681.

My invention relates to conveyers, having particular relation to such conveyers as are adapted for use in high temperature furnaces of the continuous type.

5 In its broad aspect, one object of my invention is to provide a conveyer, wherein the moving parts are wholly contained within the furnace chamber.

A more specific object of my invention is 10 to provide a conveyer comprising a moving hearth adapted to cause a periodic progression of the articles to be treated from guiding means, which serves to cause a uniform spacing of said articles in the furnace, to a 15 discharge outlet.

Another object of my invention is to provide the hearth of a furnace with a plurality of pairs of anti-friction supporting elements, together with cam-operating means for causing said hearth to have a path of travel of 20 circular-like form.

A further object of my invention is to provide mechanism for guiding the treated articles as they pass through the furnace discharge outlet into the quenching tank, the parts of said mechanism directly engaging said treated articles being returned to the inside of the furnace upon the completion of the guiding operation, whereby the temperature thereof may be maintained at substantially that of the treated articles and the formation of cold spots on said articles thus avoided.

25 A still further object of my invention is to provide conveyer mechanism for the drawing furnace, wherein the supporting surface thereof shall comprise the upper edge of a plurality of overlapping blades.

Other objects and applications of my invention, as well as details of construction and operation, whereby my invention may be practiced, will be apparent more fully hereinafter, when taken in connection with the accompanying drawings, wherein

30 Fig. 1 is a longitudinal sectional view of the hardening furnace showing, in particular, the moving hearth conveyer.

Fig. 2 is a similar view of the drawing furnace illustrating the radial blade conveyer for carrying the treated articles re-

ceived from the quenching tank through said drawing furnace to skids at the discharge end thereof;

Fig. 3 is an elevational view of the entrance end of the hardening furnace;

Fig. 4 is a similar view but showing the discharge end of the hardening furnace;

Fig. 5 is a transverse sectional view taken on the line V—V of Fig. 1;

Fig. 6 is a detail side elevational view of 60 the counter-weighted fingers for guiding the articles on the skids extending through the furnace outlet to the quenching tank;

Figs. 7, 8 and 9 are detail longitudinal sectional views illustrating the position of the hearth for successive 90° angular movements of the actuating cams from the position of Fig. 1;

Fig. 10 is an end elevational view of the drawing furnace illustrated in Fig. 2;

Fig. 11 is a transverse sectional view taken on the line XI—XI of Fig. 2;

Fig. 12 is an enlarged detail transverse sectional view of one of the conveyer chains and associated parts;

Fig. 13 is an enlarged detail side elevational view of the conveyer chain of Fig. 12;

Fig. 14 is a detail top plan view of the chain attachment shown in Fig. 13; and

Fig. 15 illustrates a detail of the invention.

My invention broadly comprises a hardening furnace 1 having a conveyer 2 for causing a periodic progression of articles

3 from guiding means 4 positioned at a furnace entrance 5 to a furnace outlet 6; a

quenching tank 7 having a skidway 8 extending from a base 9 of said tank through the furnace outlet 6 to a point adjacent to the conveyer 2; and a drawing furnace 11

having a conveyer 12 positioned to receive the articles carried out of the quenching tank 7 by a sprocket-chain belt 13 and to carry said articles through said furnace 11, discharging the same through an outlet opening 14 onto a pair of skids 15.

Referring more especially to the hardening furnace 1, as illustrated in Figs. 1 and 3 to 9, inclusive, a pier structure 16 comprises piers 17 and 18 which are spaced on opposite sides of the conveyer 2 and ex-

tended the length of the furnace. Upper sides 19 and 21 of the spaced piers 17 and 18, respectively, constitute spaced supporting surfaces for the articles to be treated. For purposes of illustration, such articles have been shown as axles having a main body portion 22 and yoke end portions 23.

The conveyer 2 comprises an elongated hearth 24 having one end 25 positioned in operative relation to the guiding means 4 and an opposite end 26 terminating adjacent to the skidway 8. Opposite sides 27 and 28 of the hearth 24 parallel adjacent sides 29 and 31 of the piers 17 and 18, respectively. An upper side 32 of the hearth 24 constitutes a supporting surface for the axles 3 when they are moved forwardly, all as will presently appear. An underside 33 of the hearth 24 comprises a pair of longitudinally extending side beams 34 and 35, which are transversely secured by channels 36.

In accordance with my invention the hearth 24 is reciprocated in a path of circular-like form extending above and below the pier supporting surfaces 19 and 21, whereby the hearth supporting surface 32 may periodically raise the axles 3 from said pier supporting surfaces 19 and 21, carry said axles forwardly a desired distance and deposit the same on the pier supporting surfaces 19 and 21 in an advanced position. Such movement causes a periodic progression of the axles 3 from the guiding means 4 at the furnace inlet opening 5 to the skidway 8 leading to the quenching tank 7. To this end, I provide sets of saddles 37 and 38, which are respectively secured on the underside 33 of the hearth 24 adjacent to the respective ends thereof. Since the two sets of saddles are substantially identical, the former only will be described in detail.

Referring particularly to Figs. 1 and 5, the set of saddles 37 are respectively mounted on the side beams 34 and 35 in such manner as to permit an independent movement of the latter, as would occur upon the longitudinal expansion of the hearth structure 24. This may be accomplished by bolts 39 which extend through slots 41 in a base portion 42 of each saddle, see Figs. 1 and 15. The set of saddles 38 at the opposite end of the hearth may be rigidly secured to the hearth structure 24, in view of the slideable mounting just described for the set of saddles 37.

Each of the saddles of the set 37 is provided with aligned pairs of depending spaced arms 43 and 44 providing mountings for anti-friction wheels or rollers 45 and 46. The wheels 45 and 46 may be provided with flat contacting surfaces 47 adapted to engage spaced points on a cooperating flat surface 48 of a cam 49 mounted on a cam shaft 51. The cam shaft 51 also provides a mounting for a second cam 52 which cooperates with spaced wheels or rollers 53—53 supported by the saddle

on the opposite side of the furnace hearth 24. Hence, provision is made for sidewise expansion of the hearth 24, as illustrated in Fig. 5, wherein it is noted that the cam 52 is provided with a groove 54 into which fits a complementary surface 55 of the spaced wheels 53—53, whereby the adjacent side 27 of the hearth 24 may be anchored to the cam shaft 51. The opposite side 28, however, of the hearth 24 may expand in view of the relatively flat contacting surfaces 47 and 48 of the wheels 45—46 and the cam 49 respectively. A shaft 56 is similarly provided with cams 57—57 for co-operation with the wheels of the other set of saddles 38, one of these cams being anchored to the side 27 of the hearth 24 to permit such sidewise expansion as occurs at this end of the hearth 24.

In Fig. 1, the hearth 24 is shown in its forward position, wherein the axles 3 have just been disposed on the pier supporting surfaces 19 and 21. The continued movement of the cam shafts 51 and 56 through an angle of 90° causes the hearth 24 to assume the position of Fig. 7, wherein it will be noted that the hearth supporting surface 32 is below that of the pier supporting surfaces 19 and 21 and that the hearth 24 as a whole has been moved toward the inlet opening 5. A further 90° movement of the cam shafts 51 and 56 actuates the hearth 24 rearwardly and upwardly, so that the supporting surface 32 thereof is in alignment with the pier supporting surfaces 19 and 21, as illustrated in Fig. 8. When the hearth is moved upwardly from this position to that shown in Fig. 9 by the continued movement of the cam shafts 51 and 56, the axles 3 are raised by the supporting surface 32 of the hearth 24 from the pier supporting surfaces 19 and 21 and carried forwardly. The completion of the cycle by the continued movement of the cam shafts 51 and 56 through 90° causes a still further forward movement of the axles 3 and the depositing of the same on said pier supporting surfaces 19 and 21 in an advanced position. The movement of the hearth 24 therefore causes a periodic forward progression of the axles 3 through the furnace.

The guiding means 4, which serves to insure a proper spacing of the axles 3 as they enter the furnace, may comprise pairs of transversely aligned shoulders 58, which are respectively formed on strips 59—59 mounted on the supporting surfaces 19 and 21 of the pier structure 16. In order to cause the axles 3 to be properly centralized with respect to the supporting pier structure 16, I provide guiding strips 61 which are respectively positioned in co-operative relation to the axle yoke 23—23 by supporting extensions 62 secured to the pier structure 16.

The loss of heat between the forward end of the movable hearth 24 and the adjacent discharge end of the furnace 1 may be pre-

vented by means of a fluid seal, as shown in Fig. 1, wherein a transversely extending channel beam 62' is so mounted on the under side of the hearth 24 that one side of said channel beam extends downwardly into fluid contained in a similar channel 63' mounted on the furnace foundation.

My invention also contemplates means whereby the axles 3 may be guided with a minimum loss of heat in their passage through the furnace outlet opening 6 over the skidway 8 into the quenching tank 7. To this end, I provide a shaft 63, which is mounted externally of the furnace 1 but adjacent to the outlet opening 6 with a pair of spaced depending arms 64. Each arm is provided with a curved projection 65 adapted to extend through a passage 66 formed between the skidway 8 and the lower edge of a movable door 67 up into the furnace chamber, terminating in a horizontal shoulder portion positioned in substantial alignment with the supporting surface of one of the piers 17-18. The skidway 8 may comprise a pair of spaced members 69-69 extending from the base 9 of the quenching tank 7 through the passage 66 between the arm extensions 65-65 and terminating at the pier supporting surfaces 19 and 21.

The spacing of the members 69 is such as to permit a forward movement of the furnace hearth 24 therebetween. During such movement, wherein the hearth 24 is moved upwardly and forwardly from the position shown in Fig. 8 to that shown in Fig. 1, the treated axle nearest to furnace outlet 6 is raised, carried forwardly, and finally deposited on the spaced supporting shoulders 68-68. The forward movement of said article on the shoulders 68-68 may be limited by abutments 72.

The spaced shoulders 68-68 now move downwardly under the weight of the axle 3, at the same time guiding said axle on the spaced skids 69-69, and are finally disengaged from the axle as it passes into the quenching tank 7. Thus, the uniform quenching of the axles 3 throughout their length is assured.

Experience has indicated that if the contacting parts of shoulders 68-68 of the guiding means are not maintained at the furnace temperature, cold spots would be formed in the axles. I, therefore, provide a counter-weight 73 for the shaft 63 sufficient to cause the contacting shoulders 68-68 to be returned to their initial position within the furnace after disengagement with the guided axle. The portion of the skidway 8 between the outlet passage 66 and the quenching tank 7 is closed by a hood structure 74 having openings 75 for the arm projections 65-65 to insure the maintenance of the axles at the hardening temperature up to the moment of quenching in the tank 7.

As illustrated in Figs. 2 and 6, the axles may be moved from the quenching tank 7 by means of the conveyer 13 say of the sprocket-chain type. The axles passing over the upper end of the conveyer 13 are guided by means of a slide 77 onto an outer end 78 of the conveyer 12. The latter enters the furnace 11 through an inlet opening 79, passing through a heated chamber section 81, the discharge outlet 14, around supporting sprocket mechanism 82, through a cooled section 83 of the furnace 11 and finally around sprocket mechanism 84 positioned externally of the furnace but adjacent to the inlet opening 79. In the passage of the axles over the slideway 77, they are automatically turned from their position shown in Fig. 5 to that shown in Fig. 11, wherein the yokes 23 instead of extending downwardly now extend horizontally, so that all parts of the axle may be positioned in the same heat zone and a uniform temperature thereby acquired.

The conveyer 12 for carrying the axles in such horizontal position through the drawing furnace 11, is particularly illustrated in Figs. 10 to 14, inclusive and comprises a pair of spaced link belts 85 and 86. The sprocket mechanism 82 at the discharge end of the furnace 11, comprises a pair of spaced sprocket wheels 87 and 88 which respectively support the outer ends of the link belts 85 and 86 and are mounted on a common shaft 89. The latter may be driven by a sprocket wheel 91 and chain 92 from a driven sprocket wheel 93. The sprocket mechanism 84 at the inlet end of the furnace 11 is similar to that just described.

Experience has shown that the portion of the link belts 85 and 86 in the heated chamber section 81 must be protected from the intense heat, otherwise the belts stretch to the extent of rendering the conveyer 12 as a whole inoperative. Accordingly, I provide guards 94 and 95 for the portions of the link belts 85 and 86 respectively positioned within the heated chamber 81. Each of the guards comprises a pier 96 extending the length of the furnace and it is provided with an inner passage 97 having a relatively narrow elongated slot 98.

The portion of the link belt which extends through the chamber 97 may be suitably supported therein by means of a member 99 of the form particularly disclosed in Figs. 12, 13 and 14. Each member comprises a base portion 101, which is riveted to a link of the belt, and downwardly spaced end portions 102 and 103 which slidably engage spaced supporting tracks 104 and 105 formed on a base portion 106 of the chamber 97, respectively. Projecting vertically from the base portion 101 through the slot 98 is a blade 107 which is angled with respect to the length of the belt and positioned in overlapping relation to a similar member on, say, a succeeding

70

75

80

85

90

95

100

105

110

115

120

125

130

link of the belt. Sides 108 and 109 of the blade 107 are flared outwardly from the base member 101, so that a relatively wide blade is formed at the upper end thereof forming a supporting edge 111. The members 99 are so positioned that as they pass around the sprocket mechanism 82 at the discharge end of the furnace 11, they do not separate sufficiently to permit an axle to drop therebetween but rather provide a continuous supporting surface. The axles passing through the discharge outlet 14 of the furnace 11 may be conveyed therefrom by the spaced skids 15 terminating in a receptacle 114.

15 The portion of the chain disposed within the chamber 97 may be maintained at a desired temperature by a pair of longitudinally extending cooling pipes 115 and 116. The cooling effect of these pipes is limited to the chamber 97 by reason of the relatively small dimensions of the slot 98 and the fact that the blades 107 extend well above the tile shield 85 into the furnace passage 81.

20 Considering the operation of my apparatus as a whole, assuming a plurality of axles on the guiding means 4 and the several driving parts actuated, the moving hearth 24 is effective by reason of its circular-like path of travel to cause a periodical progression of the 25 axles through the hardening furnace 1, finally successively depositing the axles on the counterweighted fingers or shoulders 68—68 of the guiding mechanism. As each treated axle is deposited on the shoulders 30 68—68, the latter are actuated outwardly through the furnace passage 66 under the weight of the axle but all the while guiding the axle on the skidway 8 to insure that it is uniformly quenched from end to end by the 35 oil in the tank 7. Thereafter, a sprocket 40 chain conveyer 76 carries the axles out of the quenching tank 7 and deposits the same on the conveyer 12, causing them to assume a horizontal position, wherein the yokes 23 45 are in substantially the same plane as the body portion 22. After being carried through the drawing furnace 11 by the conveyer 12, the axles are finally deposited on the skids 15 leading to a cart or other receptacle 114.

50 While I have shown only one embodiment of my invention, for the purpose of describing the same and illustrating its principles of construction and operation, it is apparent that various changes and modifications may 55 be made therein without departing from the spirit of my invention, and I desire, therefore, that only such limitations shall be imposed thereon as are indicated in the appended claims or as are demanded by the prior art.

I claim:

1. In a furnace, a hearth having a plurality of pairs of anti-friction supporting rollers, the rollers of each pair being spaced longitudinally of the hearth, and an actuating cam

individual to each pair of rollers disposed with its axis intermediate and below the axes of the spaced rollers, whereby said hearth will be supported by said cams and said rollers and may be given a reciprocatory movement 70 in a circular path.

2. A furnace having pairs of supporting rollers, and pairs of cams operatively associated with said rollers respectively, one of said pair of rollers and its co-operating cam being 75 formed to interlock.

3. A furnace hearth having pairs of rollers respectively mounted adjacent to the sides thereof, and pairs of cams respectively associated with said pairs of rollers, the cam on 80 one side only of said hearth and its co-operating rollers being interlocked to permit sidewise expansion of said hearth.

4. A furnace hearth having spaced rollers, and a shaft having a pair of cams respectively 85 associated with said rollers, one of said cams only and its associated roller being so formed as to anchor said hearth to said cam shaft, permitting sidewise expansion of the hearth relative to the other cam.

5. A furnace hearth having rollers respectively positioned adjacent to the opposite sides thereof and provided with curved and approximately flat operating surfaces, and a pair of cams associated with said rollers, 90 one of said cams being provided with a groove for said roller having the curved surface, forming an interlocking connection therebetween, the other of said cams on the opposite side of said hearth having an approximately 95 flat periphery.

6. A furnace hearth having pairs of spaced rollers respectively positioned adjacent to the sides of said hearth, and a cam individual to each pair of rollers, one of said pairs of rollers 100 and its associated cam being so formed as to cause the adjacent side of said hearth to be anchored.

7. A furnace hearth having a pair of saddles mounted adjacent to the respective sides 110 thereof, each saddle having a pair of spaced rollers, and a cam individual to each pair of rollers, and disposed with its axis of rotation intermediate and below the axes of the spaced rollers, for supporting and operating said 115 hearth.

8. A furnace hearth having a pair of spaced saddles, each saddle having a pair of spaced wheels, and a cam operatively associated with each pair of wheels, one pair of wheels and 120 its associated cam only being interlocked to cause the adjacent side of said hearth to be anchored.

9. A furnace having inlet and outlet openings, a hearth extending between said openings, a pair of saddles positioned adjacent to the respective sides of the hearth at each end thereof, each saddle having a pair of spaced supporting wheels, and a cam for said 125 pair of spaced wheels, whereby said hearth 130

may have a path of travel of circular-like form.

10. A furnace having inlet and outlet openings, a furnace hearth extending therebetween, a pair of spaced wheels rigidly mounted on said hearth at one end thereof, a second pair of spaced wheels so supported on the other end as to permit lengthwise expansion of said hearth independently thereof, and a cam individual to each pair of wheels, one of said cams and its co-operating wheels being so interlocked as to anchor one side only of said hearth, whereby sidewise expansion thereof may occur.

15 11. A furnace having openings, a movable
hearth extending between said openings, a
pair of saddles positioned adjacent to the re-
spective sides of said hearth in proximity
to one end thereof, anti-friction elements car-
ried by each saddle, a shaft extending across
20 said hearth having a pair of cams respectively
co-operating with the anti-friction elements
of each saddle, a plurality of anti-friction
elements and actuating cams operatively as-
sociated with the other end of said hearth, and
25 means for so associating said anti-friction
elements and said hearth as to permit a rela-
tive longitudinal expansion of said hearth,
certain of said elements and said cams being
30 so formed adjacent to one side of said hearth
as to permit sidewise expansion of the latter.

35 12. In a furnace, the combination with a hearth provided with a plurality of abutments in proximity to one end thereof and adjacent to the sides of the hearth, of a plurality of abutments positioned in proximity to the other end of said hearth and adjacent to the sides thereof, actuating means operatively associated with said abutments whereby a movement may be imparted to said hearth, said actuating means and said abutments being so associated as to permit side-wise expansion of said hearth, and means for so associating said abutments and said hearth
40 as to permit longitudinal expansion of the hearth relative to the abutments at one end thereof.

55 13. In a furnace having a rectilinear hearth adapted for bodily longitudinal oscillatory movement through a substantially circular path in a vertical plane, means adjacent each of the opposite ends of the hearth for supporting the hearth in a horizontal plane at all times during said oscillatory movement, the supporting means at one end of the hearth bearing a fixed relation to the hearth, and the supporting means at the opposite end of the hearth bearing a relatively movable relation to the hearth to provide for longitudinal expansion and contraction of the hearth without affecting the existing relation between the spaced supports.

14. In a furnace having a rectilinear hearth adapted for bodily longitudinal oscillatory movement through a substantially

circular path in a vertical plane, means adjacent each of the opposite ends of the hearth for supporting the hearth in a horizontal plane at all times during said oscillatory movement and for effecting said oscillatory movement of said hearth, the supporting and operating means at one end of the hearth bearing a fixed relation to the hearth, and the supporting and operating means at the opposite end of the hearth bearing a relatively movable relation to the hearth to provide for longitudinal expansion and contraction of the hearth without affecting the existing relation between the spaced supports. 70 75

15. In a furnace having a rectilinear hearth adapted for bodily longitudinal oscillatory movement through a substantially circular path in a vertical plane, means adjacent each of the opposite ends of the hearth for supporting the hearth in a horizontal plane at all times during said oscillatory movement and for effecting said oscillatory movement of said hearth, the supporting and operating means at one end of the hearth bearing a fixed relation to the hearth, and the supporting and operating means at the opposite end of the hearth bearing a relatively movable relation to the hearth to provide for longitudinal expansion and contraction of the hearth without affecting the existing relation between the spaced supports, each of the said supporting and operating means comprising a saddle for supporting the hearth, a cam located below the saddle and rotatable in a vertical plane extending longitudinally of the hearth, and a pair of spaced rollers rotatably mounted on the saddle and adapted to ride on said cam, said rollers being located at opposite sides of the center of rotation of said cam and in a common plane substantially parallel to the plane of the hearth and disposed above the said center of rotation of the cam.

16. In a furnace having a rectilinear
hearth adapted for bodily longitudinal os-
cillatory movement through a substantially
circular path in a vertical plane, means ad-
jacent each of the opposite ends of the hearth
for supporting the hearth in a horizontal
plane at all times during said oscillatory
movement and for effecting said oscillatory
movement of said hearth, the supporting and
operating means at one end of the hearth
bearing a fixed relation to the hearth, and
the supporting and operating means at the
opposite end of the hearth bearing a rela-
tively movable relation to the hearth to pro-
vide for longitudinal expansion and contrac-
tion of the hearth without affecting the exist-
ing relation between the spaced supports,
each of the said supporting and operating
means comprising a saddle for supporting
the hearth, a cam located below the saddle
and rotatable in a vertical plane extending
longitudinally of the hearth, a pair of spaced
110
115
120
125
130

rollers rotatably mounted on the saddle and adapted to ride on said cam, said rollers being located at opposite sides of the center of rotation of said cam and in a common plane substantially parallel to the plane of the hearth and disposed above the said center of rotation of the cam, means for rigidly securing the saddle at one end of the hearth to said hearth, and means for movably attaching the saddle at the opposite end of the hearth to the hearth.
